UNITED STATES PATENT OFFICE.

MAX W. WILLIAMSON, OF KIOWA, OKLAHOMA.

COTTON-GIN CLEANER.

1,045,923.

Specification of Letters Patent.

Patented Dec. 3, 1912.

Application filed December 18, 1911. Serial No. 666,409.

To all whom it may concern:

Be it known that I, MAX W. WILLIAMSON, a citizen of the United States of America, residing at Kiowa, in the county of Pittsburgh and State of Oklahoma, have invented certain new and useful Improvements in Cotton-Gin Cleaners, of which the following is a specification.

This invention relates to gin saw cleaners, designed for the purpose of cleaning the saws on a cotton gin, and one of the principal objects of the invention is to provide an attachment for cotton gins which shall be of simple construction and which will operate to clean the saws of wet cotton during the ginning operation.

Another object of the invention is to provide a cleaner for the gin saws which can be readily thrown into and out of operation without interfering with the rotation of the saws.

Still another object of the invention is to provide an attachment for cotton gins comprising a shaft having a series of cleaners mounted upon a shaft and adapted to be rotated in the opposite direction to the rotation of the saws and to revolve at a greater speed than the gin saws for removing the wet lint from the saws during the ginning operation, said cleaning device being readily thrown into and out of operative position.

These and other objects may be attained by means of the construction illustrated in the accompanying drawings, in which:

Figure 1 is a front elevation of a portion of a cotton gin and showing my cleaning attachment in position for operation; Fig. 2 is a top plan view of the same; Fig. 3 is a side elevation; and Fig. 4 is a central longitudinal section.

Referring to the drawings, the numeral 1 designates the gin saw shaft mounted to rotate in a suitable frame 2 supported on legs 3. The shaft 1 is mounted in suitable bearings 4 on the frame and the gin saws 5 are secured to the shaft in the usual or any suitable manner. Near one end of the shaft is a friction wheel 6 and outside the friction wheel is a pulley 7 connected to the shaft 1. A belt 8 surrounds the pulley 7 and leads to a suitable source of power for rotating the shaft 1.

Mounted on a shaft 9 is a series of cleaner rollers 10 which may be of wood or metal and provided with suitable notches 11 at 55 intervals and in line with the saw teeth, as shown more clearly in Figs. 1 and 2. The shaft 1 is mounted in brackets or arms 12 near the opposite ends of the shaft 9, said shaft being mounted to rotate in the 60 arms 12. The lower ends of the arms 12 are rigidly secured to a rock shaft 13 and on the end of said rock shaft is a hand crank 14. On the shaft 9 is a friction wheel 15 which may be thrown into and out of contact with the friction wheel 6 on the saw shaft, and owing to the relative sizes of the friction wheels, the cleaner shaft will be rotated at a greater speed than the saw shaft and in the opposite direction thereto. 70

The operation of my invention may be briefly described as follows: During the ginning operation, the cleaner may be readily thrown up into operative position by means of the hand crank 14 and will strip the wet, 75 lint from the saws and deliver it to the brush which is in use on cotton gins of the ordinary construction. Whenever desired, the cleaner may be thrown out of operative position without interfering with the rotation of the saws. 80

My invention is simple in construction, can be quickly attached to any cotton gin, can be readily thrown into and out of operation and is very efficient for its purpose. 85

I claim:

A cotton gin cleaner comprising a frame supported on legs, a shaft mounted in bearings near one end of the frame, a series of gin saws mounted on the shaft, a large friction roller mounted near one end of the shaft outside the frame, a driving pulley mounted on the end of the shaft nearest the friction roller, a rock shaft mounted in the frame below and to one side of the first mentioned shaft, arms secured near each end of the rock shaft and projecting at a slight angle from the vertical from said rock shaft, both of said arms lying in the same plane, a shaft mounted to rotate in bearings in the outer ends of said arms, cleaner rollers secured on said last mentioned shaft, said rollers being rounded at each end and spaced apart to provide notches, said notches alin-

ing with the gin saws, a small friction roller mounted on one end of the shaft to which the cleaner rollers are attached, said friction roller adapted to be thrown into and out of engagement with the said large friction roller, by means of a hand crank attached to one end of the rock shaft.

In testimony whereof I affix my signature in presence of two witnesses.

MAX W. WILLIAMSON.

Witnesses:

G. F. CARTER,
M. C. HAILE.
